UNITED STATES PATENT OFFICE

2,625,433

LIQUID SPRAYER

Edwin W. Vose, Orange, N. J., assignor to Spray Process Co. Inc., a corporation of New York

Application June 24, 1947, Serial No. 756,733

1 Claim. (Cl. 299—89)

1

This invention relates to improvements in liquid sprayers, and has for a principal object the provision of a liquid sprayer in which the actuating air passes through the nozzle in a full stream at low pressures, and in which, in lieu of valves or the like, a vent communicating with the vessel containing the liquid to be sprayed, is positioned so that the operator may close or uncover said vent with a thumb or finger and thereby control the operation of the device.

Another object of the invention is the provision in a liquid sprayer of a nozzle having a flanged portion adapted to form a closure for a vessel containing the liquid to be sprayed, said nozzle being adapted to have large volumes of air at low pressures continuously passed therethrough, a passage in said flange member communicating with the interior of said nozzle and with the interior of said vessel above the level of the liquid therein, means in said nozzle for deflecting air through said passage, injector means adjacent to the exit of said nozzle and communicating with liquid in said vessel below the level of the surface of liquid therein, and a vent in the wall of said flanged member communicating with the interior of said vessel and with the atmosphere, said vent being adapted to be covered by the finger of an operator, to cause said device to spray liquid from said vessel.

A further object of the invention is the provision in a liquid sprayer of a nozzle, a jar-like vessel, flanged means on said nozzle adapted to fit the mouth of said vessel, and clamping means on said vessel for securing said flange thereto, injector means in said nozzle influenced by air passing therethrough and extending into said vessel below the level of liquid therein, a passage providing communication between the interior of said vessel and the interior of said nozzle for impressing pressure on the surface of liquid therein, and vent means formed in said flange and communicating with the interior of said vessel and with the atmosphere, said sprayer being adapted to operate when said vent means is closed and pressure via said passage builds up in said vessel above the surface of liquid therein.

Yet another object of the invention is the provision in a liquid sprayer of a nozzle having injector means therein connected to the liquid to be sprayed, and a cap or thimble positioned on the end of the nozzle and having a central oval orifice formed in the end of this thimble and the further provision of at least one passage communicating with air within said nozzle and angularly disposed with respect to the axis of

the outlet of said injector means whereby air passing through said passage may react upon the discharge from said nozzle and change the shape of said discharge to another shape than conical.

5 Another object of the invention is the provision of a thimble such as described above having a central, elliptical opening in the end thereof through which the liquid sprayer passes, and a pair of oppositely disposed tubular passages lying on the short axis of the elliptical opening and angularly disposed with respect to the axis of the liquid spray, communicating with air within said nozzle and adapted to deform said spray from a conical form to an elliptical form.

10 Other objects and advantages of the invention will be apparent to those skilled in the art upon a study of this specification and the accompanying drawings, in which:

Figure 1 is a side elevation, partly in section, showing my new and improved liquid sprayer;

Figure 2 is an elevation of the device as seen from the right side of Figure 1;

Figure 3 is a plan view of the device;

Figure 4 is an enlarged fragmentary view of a portion of the device shown in Figure 1;

Figure 5 is a side elevation of a modified form of the device shown in Figure 1 devised to spray an elongated or oval swath upon an object;

Figure 6 is a view of the modification shown in Figure 5 as seen from the right side thereof;

Figure 7 is a fragmentary view similar to Figure 6 except that the thimble on the end of the nozzle is turned through an angle of 90° from the position shown in Figure 6;

Figure 8 is a sectional elevation taken along the lines 8—8 of Figure 6;

Figure 9 is a sectional view taken along the lines 9—9 of Figure 8;

Figure 10 is a sectional view taken along the lines 10—10 of Figure 8;

Figure 11 is a sectional elevation of a modification of the arrangement shown in Figure 8;

Figure 12 is a view partly in section as seen along the lines 12—12 of Figure 11; and

Figure 13 is a sectional view taken along the lines 13—13 of Figure 11.

Referring first to Figure 1, the spray nozzle 10 includes a straight tubular portion 11 having an interior passage 12 through which a stream of air may pass. Preferably the air is supplied at low pressure and large volume. Secured to the tube 11 is a flanged member, generally designated by the numeral 13, and including a portion 13 abutting and fitting the outer wall of the tube 11. A hollow portion 15 extends down-

wardly from the portion 14 and terminates in an annular flange 16, the purpose of which will be presently described. The interiors of the portions 15 and 16, designated by the numeral 17, are hollow and are in communication with the interior of the jar or vessel 18. The vessel has a mouth 19 which carries an annular stepped portion 20, which is adapted to be engaged by the interior wall of the annular portion 16, a gasket 21 being provided between the lower face of the annular flange 16 and the upper face 19 of the vessel. The vessel may carry a clamping member, generally designated by the numeral 22, and including a yoke member 23, the upper portion 23a of which is offset to partially embrace one side of the portion 15. The clamping member also includes a lever member 24, which is adapted to be raised to release the device from the vessel and adapted to be moved downwardly to clamp the device onto the vessel.

Formed in the portion 14 is a passage 25 which communicates with the interior 12 of the tube 11 and with the interior 17, and in turn with the interior of the vessel 18, which is in open communication therewith. Within the interior of the tube 11 and adjacent to the passage 25 and facing the left end of the tube 11, as seen in Figure 1, is a deflecting plate 26 which is adapted to deflect some of the air passing through the tube 11 into the space 17 and the interior of the vessel 18, so that under certain conditions to be presently described, pressure may build up on the surface of liquids within the vessel 18. Positioned within the tube 11 is an elbow 27, the male threaded portion 28 of which extends through a suitable hole in the wall of the tube 11 and which is engaged by a coupling 29. Threadedly engaging the coupling 29 is a pipe 30 which extends downwardly within the vessel 18 to a point near the bottom thereof. The upper end of the coupling 29 may seat on a shoulder 14a with a gasket 42 therebetween to form a fluid-tight joint with the portion 14.

Threadedly engaging the female threaded portion 31 of the street elbow 27 is a nipple 32 which extends parallel to the tube 11 beyond the right end thereof, as seen in Figure 1. Threadedly engaging the right end of the nipple 32 is a closed bushing or cap 33, having at least one aperture 34 formed therein. The bushing 33, near the end 34, is beveled as shown at 35. A thimble 36 has a portion 37 forming a snug fit over the right end of the tube 11 and a beveled portion 38 which terminates in an annular portion 39, the interior opening 40 of which is substantially parallel to and spaced apart from the bushing 33.

Formed in the wall of the portion 15 and communicating with the interior 17 is a passage 41. This passage has been devised to take the place of, or eliminate the necessity of a valve. When this passage is closed, for example, by the user's thumb or finger, pressure may build up within the vessel 18 above the surface of the liquid therein and force liquid up the pipe 30 and thence via the elbow 27, the nipple 32, and the opening 34 in the bushing 33 and into the air stream passing through the opening 39 surrounding the bushing 33, where it is mixed with the air and is directed toward the work.

Now, when the vent 41 is opened, any tendency for pressure to build up within the vessel 18 above the surface of the liquid is eliminated, due to the fact that the air tending to build

up such pressure and passing thereto via the passage 25 is allowed to leak out into the atmosphere, and hence no spraying is effected. The thimble 36 may be moved on the end of the tube 11 relative to the bushing 33, thereby giving the operator some degree of control over the type of spray obtained.

Another important function of the thimble or outside shell 36 is that in case the aperture 34 (or a plurality of them in cases where a plurality of apertures is used instead of one) becomes stopped up, the operator, by adjusting the thimble or shell forwardly by hand (toward the outlet of the sprayer) causes a back pressure to be produced in the liquid jet, and thus the machine may be cleaned and the shell or thimble pushed back to its normal position to place the sprayer into operation.

In Figures 5-10 inclusive a modification of the invention is shown wherein the spray nozzle 42 has a tubular portion 43, the left end 43a of which is connected via a hose or other flexible conduit 44 to a motor driven blower.

Secured to the tubular portion 43 and preferably at right angles thereto is a second tubular portion 45 the tip end 46 of which is closed and has formed therein an air passage 47 communicating with the interior of the tubular portion 43 and a second hole which will be presently described.

Joining the portion 45 and preferably formed integral therewith is an annular portion 48 which has its axis eccentric with the axis of the portion 45. The web 49 between the portions 45 and 48 forms an incline over which the locking bail 50 may be passed to engage a depression 51 formed in the surface 49 adjacent to the portion 45.

The annular portion 48 has a seating surface 52 which contacts a sealing ring or gasket 53 mounted on a shoulder 54 formed on the container 55.

The bail 50 has parallel depending portions 56 and 57 which respectively engage loops 58 and 59 formed in a generally U-shaped lever member 60 which oppositely engage loops 61 and 62 formed in the fixed embracing ring 63 which embraces the vessel or container 55.

When securing the nozzle on to the vessel 55, the nozzle is positioned on the vessel as shown in Figure 5 with the lever 60 shown in the position shown in the dot-dash lines and the bail 50 is swung to the position shown in dot-dash lines.

The operator, after making sure that the gasket 53 is properly positioned between the seating face 52 and shoulder 54, swings the lever 60 downwardly to the position shown in solid lines, with the result that the bail 50 assumes the position shown in solid lines in Figure 5 and during the latter portion of the movement of the lever 60 the bail 50 exerts sufficient force to tension the gasket 53 and thereby a contact seal is effected between the vessel and the nozzle.

Returning to Figure 8, a threaded nipple 64 has its tip end threadedly engaging the portion 65 of a T fitting 66. The upper end of the nipple 64 has a beveled seat 67 formed thereon which is adapted to be engaged by the beveled end 68 of a valve element 69. The valve element has a threaded stem 70 which threadedly engages a bushing 71 which extends through the wall of the tubular portion 43 and which threadedly engages the leg 72 of the T fitting 66. The stem 70 has a knob 73 on the upper end thereof by means of

which the valve member 69 may be propelled toward or away from the seat 67.

The nipple 64 extends through a hole 74 formed in the end 46 and is secured therein by means of a nut 75 which abuts the closed end of wall 46.

Threadedly engaging the lower end 76 of the nipple 64 and extending downwardly to a point adjacent to the bottom of the vessel 55 is a pipe 77. Mounted on the pipe 77 adjacent to the lower end of the passage 78 formed within the portion 45 is a disk 79 which defines a passage 80 between its perimeter and the lower edge of the passage 78. The purpose of this disk is to define a narrow passage through which air may freely pass downwardly but which discourages slugs of liquid from passing in the opposite direction.

The leg 81 of the T 66 has its axis substantially on the center line of the tubular portion 43 and threadedly engaged by one end 83 of a nipple 82, and a lock nut 84 with a washer 85 between it and the end of the portion 81 securely locks the nipple 82 therein.

The outer end 86 of the nipple 82 is threadedly engaged by a tip 87 which may have formed therein one or more holes 88.

The right end 43a of the tubular portion 43, as may be seen in Figure 8, has a plurality of longitudinal slots 89 formed therein so that fittings may be firmly mounted thereon without binding, due to the fact that the portions of the wall between the slots are springy.

A thimble generally designated by the numeral 90, has a straight portion 91 which fits over the end 43a of the air tube 43 and an angular portion 92 formed integral therewith with an inward bead 93 formed therebetween. The bead 93 forms a shoulder which abuts the end of the air tube 43 and therefore forms a step for the thimble 90.

The thimble 90 has an end wall 94, with an oval or elliptical opening 95 formed therein. In Figure 6, the opening 95 is shown with its long axis horizontal. It will also be noted that the hole 88 in the tip 87 is positioned in alignment with the point where the horizontal and vertical axes of the elliptical opening 95 cross each other.

The end wall 94 of the thimble has a threaded hole 96 formed therein. This hole is spaced apart from the elliptical opening 95 and has its axis forming a predetermined angle with the axis of the air tube 43.

Mounted in the threaded hole 96 is a short threaded nipple 97, the outer extremity of which extends beyond the tip 87. A second angularly threaded hole 98 is formed in the end wall 94 and this hole is substantially equi-distance from the axis of the tip 88 and has its axis forming substantially the same angle with the axis of the air tube as that of the axis of the hole 96.

Mounted in the hole 98 is a threaded bushing 99 which is preferably identical with the bushing 97. When the spray gun is being operated, the spray leaving the tip 88, which would be normally conical in form, is influenced by air passing from the air tube 43 via openings in the nipples 97 and 98, and is thereby distorted and changed to substantially an elliptical cross section, and therefore the device deposits upon the surface against which the spray is directed, an elongated or oval swathe of the fluid being sprayed.

It will be noted that in the arrangement shown in Figures 5-10 inclusive, the spray gun has no operating valve. A hole 100 is formed in the wall of the tubular portion 45, and the gun is operated as follows:

When air is passing through the air tube 43 and the hole 100, which might be termed "the operating vent" is open, air passing into the passage 78 via the hole 47 passes on out to the atmosphere via the operating vent 100 and consequently no pressure can build up within the vessel 55.

Now, as soon as the operator wishes to cause the gun to spray, he covers the operating vent 100 with a thumb or finger and immediately the pressure starts to build up within the vessel 55, due to the fact that air passing into the vessel via the passage 78 and the hole 47 cannot escape, and therefore this pressure is exerted upon the surface of the liquid within the vessel, forcing it up through the pipe 77, the nipple 74, the T fitting 66 and the nipple 82 to the opening 88 formed in the tip 87.

Due to the fact that air passes over the tip 87 via the elliptical opening 95, a partial vacuum is produced which abets the removal of liquid from the nipple 82 and causes it to form a spray.

Now, as a spray leaves the opening 95, it is influenced by jets of air passing through the nipples 97 and 99 and its shape is changed from conical to oval or elliptical and it is deposited on the surface being treated in the form of an elongated swathe of the fluid medium being sprayed.

If the thimble 94 is in the position shown in Figure 6, the elongated swathe deposited on the surface is horizontal. Due to the fact that the end of the air tube is provided with slits 89 so that the webs therebetween springingly engage the thimble, the thimble may be rotated on the end of the air tube. From this it will be seen that the worker may deposit an elongated swathe on the surface of the work with the axis of the swathe extending in any desired direction.

Suppose that it were desired to have the swathe extend vertically; the thimble 90 would be rotated on the end of the air tube 43 to bring it into the position shown in Figure 7 where the major axis of the ellipse 95 is vertical. Obviously, the thimble may be set with the elongated axis of the ellipse in any desired position between the two above described positions.

In cases where the paint or other material being sprayed contains solid matter which can settle to the bottom of the vessel, the modification shown in Figures 11, 12 and 13 is important.

Referring to these figures, it will be noted that elements like those shown in Figures 5-10 have been given the same numerals as the corresponding elements in the Figures 5-10 except that they are followed by the letter "a." For example, the vessel containing the fluid to be sprayed is designated in Figures 11 and 13 by the numeral 55a, etc. Since the description of these elements is clearly set forth in connection with Figures 5-10, it is believed that this description need not be repeated.

The hole or passage 47a communicates with a threaded hole 101 formed in the wall 46a, and engaging this threaded hole is a fitting 102 which is in turn secured to the upper end of a tube 103. The tube 103 has its lower end curved as at 104 and terminating at 105 with its axis substantially horizontal.

By this arrangement the air entering the vessel, instead of being directly impressed upon the surface of the fluid in the vessel, as is the case in the arrangement shown in Figures 5-10, is delivered below the surface of the fluid, in fact, in the bottom of the fluid, and due to the curved arrangement of its lower end as shown in 104 and 105 in Figure 13, this air agitates the fluid within

the vessel at the bottom thereof, and consequently any solids are constantly stirred and intermixed with the fluid so that the mixture always passes up the tube 71a to be sprayed.

It will be noted that the end 105 of the tube 103 terminates above the lower end of the pipe 71a and is therefore arranged so that none of the agitating air from the tube 105 enters the pipe 71a, but instead, this air agitates the fluid and then rises to the upper portion of the vessel 55a and exerts pressure on the surface of the fluid.

Instead of using a disk such as the disk shown in Figure 8 to separate the chamber 78a from the space above the surface of the fluid, a member 106 is employed. This member has a disk-like body 107 which has a slot 108 formed therein to straddle the pipe 71a and has a leg 109 projecting oppositely therefrom through which a screw 110 passes and threadedly engages a correspondingly threaded hole 111 formed in the web 49a. This leaves a space 112 between the member 106 and the walls of the passage 78a, which corresponds to the space 80 shown in Figure 8. The device operates exactly the same as described in connection with Figures 5-10 and the pipe 103 performs the additional function of agitating the fluid in the bottom thereof.

Although the device shown in Figures 11 to 13 is described above as a liquid sprayer, I do not wish to be limited to its use as a liquid sprayer because I have found that the principle employed therein for agitating the liquid with the vessel 55a will also agitate divided solids and this principle has actually been used by me in devices for spraying powders, granules, flock, and other divided animal, vegetable, and mineral materials.

Although I have herein shown and described an improved spray gun and two modifications thereof, it is obvious that many changes may be made in the arrangement shown and described within the scope of the appended claim.

What is claimed is:

In a liquid sprayer an elongated tubular member one end of which is adapted to be connected to a source of actuating air, flange means on

5 said member intermediate the ends thereof for attaching said nozzle to a vessel for containing liquid to be sprayed, jet means including a fitting mounted in said nozzle intermediate the ends thereof and including a conduit extending through said flange means and terminating below the level of liquid in said vessel, tubular means within said member and substantially concentric therewith and forming an outlet for said jet means, said tubular means having one end connected to said fitting and having its other end threaded, an apertured tip threadedly engaging said threaded end and adapted to be adjusted axially thereon, and a thimble mounted on the 10 discharge end of said nozzle and movable axially thereon, said thimble having an aperture formed therein embracing said tip and being adjustable axially on said nozzle for regulating the spray and for effecting back pressure for cleaning said 15 apertured tip.
